D. P. GLEASON

BARRETTE

Filed April 3, 1922

Inventor
Dora P. Gleason

By *Walter F. Murray*
Attorney

UNITED STATES PATENT OFFICE.

DORA P. GLEASON, OF CINCINNATI, OHIO.

BARRETTE.

Application filed April 3, 1922. Serial No. 548,899.

To all whom it may concern:

Be it known that I, DORA P. GLEASON, a citizen of the United States of America, and a resident of Cincinnati, in the county of 5 Hamilton and State of Ohio, have invented a new and useful Improvement in a Barrette, of which the following is a specification.

My invention relates to barrettes of a type 10 to be employed primarily upon the tresses of girls.

An object of my invention is to provide a barrette which is especially adapted to be mounted upon a large mass of hair which 15 girls ordinarily permit to hang loosely over their shoulders, and is intended to function as a fastening means adapted to hold the hair in one bunch or mass.

Another object of my invention is to provide 20 a barrette for the purpose stated which will securely retain the hair.

Another object of my invention is to provide 25 a device for said purpose, which has esthetic as well as utilitarian features.

Another object of my invention is to provide 30 a barrette that may be readily applied and removed in a novel and simple manner.

Another object of my invention is to utilize 35 the expansion of the parts of the barrette occasioned by passing the hair between the parts of the barrette, to augment the holding or locking of the barrette parts.

These and other objects are attained by the 40 means described herein, and disclosed in the accompanying drawing, in which:—

Fig. 1, is a fragmental view of a bunch of hair having mounted thereon a barrette embodying my invention.

Fig. 2, is a perspective view of a barrette 45 embodying my invention in an open or inoperative condition.

Fig. 3, is a cross-sectional view, on a reduced scale, on line 3—3 of Fig. 1.

Fig. 4, is a fragmental perspective view 50 of a spring end of the barrette.

Fig. 5, is a view showing the form assumed by the barrette when opening same.

The barrette 6, comprises a single band having an eye 7, formed intermediate its 55 ends, whereby a front 8, and a back 9, is formed. The front and back are crimped immediately adjacent the eye 7, as is shown at 10 and 11, whereby certain spring qualities are imparted to the barrette. The free end of the front is hooked as shown at 12, and the free end of the back is adapted to lodge

in the hooked portion of the front. The back is made slightly shorter than the front, and is of a width substantially equal to the width of the front. The band is preferably 60 of considerable width, whereby extended clamping faces are formed on the front and back, adapted to engage the hair 13. The front of the band is provided with a series of transverse slots 14, whereby the front of 65 the barrette is weakened in comparison to the back. It is desirable to give these transverse slots preferably a crescent form, thereby adding to the artistic qualities of the barrette, and providing means for the 70 threading of a ribbon 15, through the face of the barrette while at the same time accomplishing the weakening referred to.

When a barrette embodying my invention is secured upon a bunch of hair, the front 75 of the barrette being somewhat weaker than the back, bulges outwardly to a greater extent than does the back 9, wherefore the free end of the back 9, is securely locked in the hooked end 12 of the front. By referring 80 to Fig. 3, it will be apparent that the greater the mass of hair, the tighter will the back 9 be held by the hooked end of the front. Because the barrette is of considerable width, the barrette has an extended binding face on 85 both its front and back. Therefore, the barrette will secure the bunch of hair very firmly. When it is desired to disengage the free end of the back from the hook, the thumb of one hand is brought into engagement with the rear of the hooked end, and the eye is grasped by the fingers of the other hand. Pressure is then directed upon the band, so as to tend to convex the barrette to a position such as is shown in Fig. 5. When 90 the barrette has been convexed to a sufficient degree, so as to extend the hook beyond the free end of the back, the free end of the back will snap away from the front of the barrette. A bunch of hair 13, may then be inserted between the front and back of the 95 barrette. The barrette is then convexed in the same manner as previously described, except that a thumb or a finger engages the free end of the back, so that when the barrette has been convexed sufficiently to permit the free end of the back to clear the hook on the front, the free end of the back will be moved into the seat 16, formed in the hooked end of the front, whereby the free 100 end of the back is retained in engagement with the hooked end of the front. Due to

the front of the barrette being weaker in spring quality than the back, the back extends in a substantially straight line, while that portion of the front intermediate the ends of the barrette, bulges away from the back sufficiently to accommodate any quantity of hair upon which the barrette is to be mounted.

What I claim is:—

10. 1. As a new article of manufacture, a flexible barrette having a front and a back adapted to be secured upon one another at their ends, the front having transverse slots, thereby being weakened in relation to the 15 back, whereby the back is given the greater rigidity against flexing.
2. As a new article of manufacture, a barrette comprising a single broad flat flexible band of a substantially uniform width, 20 turned on itself intermediate its ends, whereby to form a front and a back, the front

having transverse slots whereby the flexibility of the front is increased beyond the flexibility of the back, and means to secure the free ends of the band upon one another. 25

3. As a new article of manufacture, a barrette comprising a single broad flat flexible band of a substantially uniform width, turned on itself intermediate its ends, whereby to form a front and a back, the front having transverse slots whereby the flexibility of the front is increased beyond the flexibility of the back, the front having a hook formed on its free end and the back being slightly shorter than the front, the free end of the back being adapted to seat in the hook whereby the front is flexed to accommodate a bunch of hair. 30

In testimony whereof, I have hereunto subscribed my name this 30th day of March 40
1922.

DORA P. GLEASON.
